CANNING
MACHINE

A schematic diagram of a cutting machine setup. It shows a rectangular frame with a central vertical column. On the left, there is a small rectangular component with a vertical line through it. On the right, there are two vertical lines, each with a horizontal line extending from its top. The entire assembly is labeled 'CUTTING MACHINE' in a handwritten-style font.

The diagram illustrates a cutting machine setup. On the left, a 'CUTTING MACHINE' is shown with a small schematic of its internal components. To its right is a 'CLEANING MACHINE' represented by a rectangular box with a hinged door. Above the cleaning machine is a scale with a rectangular platform. The scale has markings for weight: 0.0, 1.0, 2.0, 3.0, 4.0, 5.0, 6.0, 7.0, 8.0, 9.0, 10.0, 11.0, and 12.0. An arrow points from the cutting machine towards the scale.

A technical line drawing of a mechanical assembly. The drawing shows a base structure with several vertical rods or bars extending upwards. Some of these bars have small rectangular blocks attached to them. The components are labeled with numbers: 1, 2, 3, 4, 5, 6, 7, 8, 9, 10, 11, 12, 13, and 14. The labels are placed near their respective parts, with some labels like 10, 11, 12, 13, and 14 appearing twice. The style is a simple technical sketch with no shading or color.

AUTOMATIC FISH-CLEANING DEVICE

Albert Vincent Sullivan, San Francisco, Calif., assignor to California Packing Corporation, San Francisco, Calif., a corporation of New York

Application September 21, 1936, Serial No. 101,690

12 Claims.

(Cl. 17—3)

The present invention is directed to an automatic device whereby fish varying in size may be automatically and rapidly beheaded, de-tailed, gutted and cleaned. The apparatus of this invention is particularly adapted for use in canneries or other establishments in which large quantities of fish of the same species but varying in size have to be cleaned preparatory to cooking, rendering, canning, or other operation. The device of this invention thoroughly cleanses the fish without wastage and has been employed with great success in the cleaning of mackerel prior to canning and cooking.

Prior large scale operations of fish cleaning, particularly on fish such as mackerel (as distinguished from salmon and other large fish) involved tremendous amounts of manual labor and were thus extravagantly time-consuming. Such manual cleaning methods have often been unsatisfactory and incomplete, the operators permitting some of the internal organs to remain in the visceral cavity. The present invention relates to an apparatus which rapidly and economically beheads and de-tails the fish, the device automatically compensating for fish of varying length so that unnecessary amounts of flesh are not cut off simply because the fish are of varying lengths. Moreover, the cleansing device of this invention assures complete removal of all internal organs including those tenaciously adhering members and membranes which ordinarily are to be found in the visceral cavity adjacent the backbone of the fish. As many as sixty fish per minute may be automatically and continuously handled by the device of this invention.

Generally stated, the machine of this invention comprises a combination of conveyors, the feeding conveyor being provided with means for holding fish in a transverse position. Means are also provided for beheading the fish and for cutting off the tails of the fish.

Means are also provided for moving the fish transversely of the conveyor in a desired operative relation with the tail cutting means, such means cooperating with gage means for limiting the transverse movement in accordance with fish thickness. Means are then provided for carrying the fish in a vertically inverted position along a path of travel. Ripping, gutting, scraping and washing means are then positioned in such line of travel so that the fish upon being discharged from the machine are in thoroughly cleansed condition.

An object of this invention, therefore, is to disclose and provide an automatic fish cleaning

machine capable of receiving fish of various sizes and discharging them in cleansed condition, maximum quantities of clean edible fish being produced.

Another object of the invention is to disclose and provide automatic means for beheading and de-tailing fish, the de-tailing means being automatically adjustable in accordance with the fish thickness and not dependent upon length of the fish.

A further object of the invention is to disclose and provide means for supporting and conveying fish past a plurality of cleansing and de-gutting means.

A still further object of the invention is to disclose and provide a combination of elements and means for driving the same in timed relation.

Other objects, uses, advantages, modifications and adaptations of the invention will become apparent to those skilled in the art from the following detailed description of one preferred embodiment of a complete machine, shown in the appended drawings for purposes of illustration. In such drawings:

Fig. 1 diagrammatically represents the cleaning machine of this invention and its relationship to other units, such as a cutting machine and canning machine in a fish cannery.

Fig. 2 is a plan view of the entire cleaning machine.

15 Fig. 20 is a detailed face view of a pinion and crank employed in the device shown in Figs. 18 and 19.

Although a number of elements, movements and devices embodied in the illustrative form of apparatus are capable of being used in other machines, the description given hereinafter shall be particularly directed toward a complete fish handling and cleaning machine adapted for use in canneries, for the purpose of facilitating understanding. In canneries, large quantities of 20 fish of the same general species or type are cleaned, cut into desired lengths (generally substantially equivalent to the height of the can in which they are to be packed) and then placed in the cans. The fish are then cooked and the cans sealed. Obviously, numerous changes from this 25 general method of operation are utilized by the canners, depending upon the type of fish, the type of pack, etc.

A general arrangement often used is illustrated 30 in Fig. 1 wherein the cleaning machine so identified receives fish from a feeding conveyor indicated at 2, the cleansed fish being then discharged by a conveyor 3 onto another conveyor 4 which feeds the fish to the cutting machine. This machine cuts the fish into desired lengths and such lengths are then arranged upon a conveyor 5 which supplies the cut fish to a canning machine.

As shown in Figs. 2, 3 and 4, the cleaning machine to which this invention is primarily directed 35 comprises a base provided with an extension 1 which supports a feeding conveyor 2.

As shown in more detail in Fig. 7, the feeding conveyor 2 may consist of a pair of continuous chains 6 carrying transverse members provided with upwardly extending fingers as indicated at 7. These fingers extend through a stationary table formed of longitudinal members 8 adapted to support the fish. Gill hooks 9 (shown in more detail in the perspective of Fig. 8) are attached 40 to the fingers 7, the major portion of the gill hook extending forwardly of the fingers. These gill hooks 9 are adapted to enter the gill of the fish when the fish is laid on its side with its back pointing in the direction of travel of the conveyor 2. Each of the gill hooks 9 is provided with 45 an upwardly and outwardly extending portion so that some free space exists below the plane of the table 8 on which the fish is slidably pushed by the conveyor 2. The continuous chains 6 of the conveyor 2 pass over suitable sprockets journaled on an adjustably positionable stud shaft, generally indicated at 10, and on similar sprockets 11 mounted upon a driven shaft 12, the details of such shaft and drive being more clearly 50 shown in Fig. 19. The sprockets 11 and the entire feeding conveyor 2 may be driven intermittently.

Fish are manually attached to the gill hooks 9 during periods of dwell of the conveyor 2. The 55 fish, as has been stated, are placed with their

backs facing the direction of travel. A plurality of presser shoes 13 are positioned above the feeding conveyor 2, such shoes being adapted to yieldably hold the fish on the feeding conveyor during the beheading and de-tailing operations. These shoes 13 are preferably supported by means of rods extending through a supporting frame 14, springs being employed for the purpose of yieldingly forcing the shoes against the fish. These shoes maintain the fish in position on the slotted table 8 while they are beheaded by a cutting means, such as the saw 15. The saw 15 is mounted upon a driven shaft 16 carrying a sprocket 17 operably connected to another sprocket on a jack shaft 18, which jack shaft is then driven by suitable sprocket and chain means from a driving shaft 19 (see Fig. 2). The cutting saw 15 is positioned in a vertical plane which misses the gill hooks 9, as is most clearly shown in Fig. 6, and therefore beheads the fish, the cut being 20 made immediately back of the gills of the fish.

The next operation to which the fish are subjected is that of de-tailing. As the fish is moved away from the saw 15, its tail enters a vertically adjustable gage means. Such gaging means include a lower member 20 with its upper surface substantially in the plane of the slotted table 8 and a vertically adjustable upper member 21 mounted on a suitable holder 22. The space between members 20 and 21 determines the thickness of fish adjacent the tail which is to be cut off and discarded. Since some fish may be materially shorter than the width of slotted table 8, means are provided for yieldably introducing the tail of the fish into the gaging means including members 20 and 21. Such means are more specifically shown in Figs. 5 and 6 and comprise a reciprocating pusher provided with a head 23 mounted on rods 24 passing through suitable supports 25. The means for yieldably urging the pusher head 23 against the neck of the beheaded fish includes an internal cam 26 mounted upon a shaft 27. A bell crank provided with arms 28 and 29 is pivotally mounted at 30, the arm 29 being provided with a roller 31 cooperating with a cam groove 32 formed in the cam 26. The arm 28 is provided with a pivoted auxiliary arm 33 which is yieldably urged toward the arm 28 by means of a pin 34 and a spring 35. The ends of the arms 28 and 33 are provided with dogs adapted to engage with a member 36 attached to the rods 24. From an examination of Fig. 6 it will be seen that during the rotation of the cam 26 the bell crank lever, including arms 28 and 29, will be pivotally moved around the point 30.

The advance of the head 23 against the neck of the fish is accomplished by means of the yieldably held arm 33 so that when the tail of the fish completely enters the limiting space between the members 20 and 21, further rotation of the cam 26 will not force the fish any further, the resistance offered by the gaging members 20 and 21 overcoming the tension of the spring 35 which holds the arm 33. The second portion of the cam cycle causes the arm 28 to move to the right (referring to Fig. 6), withdrawing the pusher head 23.

The tail of the fish is then cut off by means of a suitable cutter such as the saw 38. The cutting saw 38 may be mounted upon the jack shaft 18 referred to hereinbefore.

In view of the fact that the back of the fish is generally provided with fins which would engage with the upstanding fingers 7 of the con-

veyor and thereby impede the transverse movement of the fish towards the gaging means 20—21, means are provided for temporarily liberating the fish from contact with the fingers 7. Such means comprise a rocker shaft 39 transversely positioned above the feeding conveyor, the rocker shaft 39 being provided with a downwardly extending member 40 provided with a series of fingers 41 adapted to extend between the fingers 7 and the longitudinally extending presser shoes 13. This rocker shaft 39 is periodically energized and moves the fish away from the fingers 7 into the position shown in Fig. 5.

The movement of the member 40 is then rapidly reversed, permitting the pusher 23 to move the fish into the gage means 20—21 before the fingers 7 can contact with the fish and proceed in advancing the same toward the cutting wheel 38. The rocker shaft 39 may be actuated by means of a crank 42, a link 43 and a bell crank lever 44 (see Fig. 4), the lower end of the bell crank lever being provided with a roller 45 in engagement with an internal cam 46 driven by a shaft 47 (see Fig. 17). It is to be understood that the movement of the rocker shaft 39 and member 40 is timed with respect to the movement of the pusher 23 and the movement of the feeding conveyor 2.

After the fish have been beheaded and de-tailed in the manner described, they are then discharged from the feeding conveyor 2 over the downwardly curved table portions 50 shown in Fig. 4 onto the auxiliary conveyor mounted upon the sprocket 51 (Fig. 4), said auxiliary conveyor being substantially at right angles to the direction of travel of the feeding conveyor 2. The fish now land upon this auxiliary conveyor in a vertically inverted position, i. e., belly up. The sprocket 51 carries a continuous conveyor chain 52 provided with upstanding dogs 53. The forward end of the chain 52 passes over a second sprocket 54. The dogs 53 are spaced a distance slightly in excess of the distance separating the planes of the cutting means 15 and 38 used for beheading and de-tailing the fish.

The auxiliary conveyor moves the fish into a conveying means which then brings the fish into operative relation with a plurality of cleaning devices. This cleaning conveyor is shown in plan in Fig. 9 and comprises a pair of opposing continuous chains 60 and 61 preferably mounted in a substantially horizontal plane, the chains 60 and 61 carrying a plurality of projecting points 62, as more clearly illustrated in Fig. 11. The opposing sides of the conveyors 60 and 61 are guidingly supported upon parallel rails 63 attached to a frame 64. If desired, a trough-like member 65 may be adjustably positioned between the two opposing lays of the conveyors 60 and 61, adjustment means being provided such as, for example, the screw and bolt means 66—67, such bolt means cooperating with the brackets or frames 64 attached to the base of the machine.

In order to properly position and feed the fish into the cleaning conveyor, suitable guiding means may be provided between the sprocket 54 and that point of the conveyor at which the pointed members 62 actually enter the back of the fish and hold the fish in position. One form of adjustable guiding means is illustrated in Figs. 15 and 16. This positioning and guiding device is generally indicated by the numeral 70 and is positioned at a point above the sprocket 54 and between the auxiliary conveyor carried by said

sprocket and the cleaning conveyor comprising elements 60 and 61.

As shown in Figs. 15 and 16, this device may include a body portion 71 provided with two segmental gears 72 mounted on pins extending through the body portion. The segmental gears 72 carry downwardly depending spaced plate members 73 which normally tend to approach one another under the influence of a connecting bolt and spring combination indicated at 74. The forward portions of the plate members 73 are outwardly curved. Since the segmental gears interlock, angular positioning of the members 73 takes place simultaneously and equally. A flat spring member 75 carried by the body portion 71 tends to hold the fish down.

The conveyors 60 and 61 hold the fish by reason of the prongs or points 62 entering the back of the fish and in this manner the fish is carried past a plurality of cleaning devices. In operative relation to the path of travel of the fish on the conveyor and on the channel 65 there are positioned a cutting means, such as the rip saw 76, a gutting tool 77, a scraping tool 78, a longitudinal wiping wheel 79 and a transverse wiping tool 80. The rip saw 76 and the gutting tool 77 are preferably mounted as a single unit on a supporting member 81 pivoted about a stud 82. The other end of the member 81 is formed into a gutting tool 77 and suspended from a member 83 by means of a rod 84 and spring 85 whereby the devices 76 and 77 may yieldably press against the fish. The rip saw 76 is driven through a flexible coupling 86 (such as a flexible hose or universal joint) by a driven shaft 87 having a mitre gear connection with the driving shaft 19 (see Fig. 2).

In the event the weight of the members 76 and 77 is sufficient, spring 85 can be eliminated or it may be introduced between the top of the rod 84 and the member 83 for the purpose of relieving some of the load or pressure applied to the fish. After being ripped along the belly and gutted, the fish then moves in contact with the scraping tool 78, which is provided with a rounded nose adapted to enter the visceral cavity, and with a removable scraping member 88. This scraping member 88 is particularly designed to scrape the closely adhering membrane and organs found in the visceral cavity adjacent the backbone of the fish. After being scraped in this manner, the visceral cavity of the fish is wiped out by means of a revolving wheel 79 which may be constructed in a number of different ways. As shown, the wheel 79 is provided with a plurality of outwardly extending rubber or other resilient and flexible members 89. While being scraped out by the wheel 79 the outer surfaces of the fish are supported by means of curved members 90 (see Figs. 10 and 13). Thereafter the visceral cavity of the fish is maintained open by means of members 91 which may form a part of a member connecting the scraping elements 78 and the bearing for the wheel 79. The wheel 79 is preferably mounted in a yoke 92 pivoted about a stud bolt 93. The member 91 as well as the wheel 79 may be maintained in floating position above the path of travel of the fish by means of a rod and spring arrangement indicated at 94.

After being ripped, gutted, scraped and wiped, the fish is further wiped by a transverse movement. Since the belly walls of a fish are quite thin, such transverse movement would ordinarily tear the flesh and otherwise disfigure the fish.

The transverse movement is imparted by means of a substantially conical member 80 mounted for rotation within a tube 95 upon a shaft 96. The member 80 may be made of molded rubber or the like. The members 91 protect the inner walls of the visceral cavity as illustrated in Fig. 14, permitting the wiping tool 80 to thoroughly cleanse that area of the cavity adjacent the backbone. During such cleansing operation the exterior walls of the visceral cavity are supported by means of curved members 97. The shaft 96 and the member 80 revolve about an axis longitudinally disposed with respect to the fish and substantially at right angles to the plane in which the wiping wheel 79 rotates. The wiping element 80 is floatingly suspended from the support 83 by means of a bolt and spring suspension indicated at 98.

After these various elements have operated upon the fish, it will be found that the fish is thoroughly clean. Occasionally some small flecks of material may be found within the visceral cavity and for this reason a suction pipe 99 may be caused to extend into the visceral cavities of the fish, such suction removing any liquor or small remaining particles. It is to be understood that supplies of flushing water may be introduced along the lines at various points as indicated at 100, 101 and 102 for the purpose of removing visceral remains and assisting in cleaning the fish.

The shaft 96 which carries the transverse wiping tool 80 is driven through a mitre gear carried on a jack shaft 103. This jack shaft is driven through mitre gears (shown in Fig. 2) from the driven shaft 19. This driven shaft also drives the longitudinal wiping wheel 79 through a flexible connection 104 and the rip saw 76. It is to be observed that the same driving shaft 19 supplies power to the saws 15 and 38 in the manner described hereinbefore. Means for driving the shaft 19 are not shown but may take any suitable form.

Although all of the moving parts of the complete machine may be driven from a single source, it is preferred to have two separate drives, one for the relatively high speed elements, such as the saws and wipers above described, and another for the conveyors, rocker arms, etc. The main drive shaft shown in the drawings is indicated at 105 and by means of suitable reduction gearing 110-111 drives the shaft 47 (see Fig. 17). The shaft 47 is provided with a mitre gear 106 which is in engagement with mitre gears carried by two short shafts, namely, shaft 27 and shaft 108. The latter carries sprocket 51 which drives the auxiliary conveyor. The former shaft 27 carries the cam 26 which actuates the pusher 23 (see Figs. 5 and 6 for further details).

The gear 111 carried by the shaft 47 may also drive a large gear 112. This large gear may be journaled upon a stationary stud shaft 113 (see Figs. 18-19). The gear 112 carries a pair of diametrically opposed pins 114 and 115 extending beyond the face of the gear. A pinion is mounted on each of these pins, the pinions being identified at 116 and 117. Each of the pinions is provided with a crank, such as 118 and 119, and each of the cranks carries a roller, the rollers being indicated at 120 and 121. The cranks, such as crank 118, may be firmly attached to the pinions by means of screws or the like, as shown in Fig. 20.

75 The pinions 116 and 117 are in engagement

with a fixed spur gear 122 keyed to the stationary stud shaft 113. The gear 112 is continuously driven and during rotation thereof the pinions 116-117 travel about the circumference of the fixed gear 122. The rollers 120 and 121 are slidably positioned within a yoke member 123 provided with slots in alignment. The yoke 123 is firmly attached to a tubular shaft 12 journaled upon the stud shaft 113. By means of the elements described the continuous rotation of gear 112 is transformed into an intermittent rotation of the tubular shaft 12. For example, when it is assumed that the roller carried by the crank attached to one of the pinions is in the bottom of a slot in the yoke member 123 and in the position indicated at A in Fig. 18, rotation of the gear 112 through one-half revolution will cause the roller to move upwardly in such slot and then downwardly into the position indicated at B. During this cycle of operations the yoke 123 revolves rapidly during the central portion of the path and is substantially stationary at points A and B. In other words, every rotation of the gear 112 is converted by the elements described into two rapid partial rotations with intervening dwell periods, such intermittent rotation being then transmitted to the tubular shaft 12, sprockets 11 carried thereby and the feeding conveyor 2 driven by said sprockets.

It is to be understood that although a particular method of driving the apparatus has been described, other driving means may be employed and those skilled in the art will have no difficulty in adapting the various units, movements and combinations of elements disclosed herein to the circumstances and conditions encountered in various adaptations of the invention.

The shaft 47 may extend along the machine and terminate in a mitre gear 130 which is in engagement with a mitre gear 131 mounted upon a shaft 132. This shaft is suitably journaled and is provided with mitre gears capable of driving sprockets 133 and 134 in opposite directions (see Fig. 9). These sprockets then carry the continuous conveyor chains 60 and 61. Idler sprockets 135 and 136 are also provided at the opposite end with two or more additional guiding sprockets for the purpose of maintaining the conveyor chains taut and gradually bringing such chains to the required distance apart, thereby permitting the prongs 62 to enter the fish near the feed end.

Since a description of the mode of operation has accompanied the description of the mechanical construction of the device, it is not necessary to review the entire mode of operation of the machine. It will be observed that the fish are intermittently fed into the machine, permitting the operators to attach the fish to the feeding conveyors by means of gill hooks. The gill hooks insure beheading of the fish at a point immediately in back of the gills. The fish are then moved transversely into engagement with gaging means after the fish have been liberated from the prongs of the feeding conveyor for the purpose of clearing the fins. The gaging means properly position the fish with respect to the detailing saw so that no excessive quantity of fish is cut off but instead the entire tail and but a very small portion of the body of the fish are cut off. The fish are then moved onto the auxiliary conveyor and properly placed thereon in a vertically inverted position whereupon they are picked up by the cleansing conveyor, being held by the points 62. During cleansing, the belly of the fish is ripped open and the fish are de-gutted, 75

scraped and repeatedly wiped and rinsed. As a result, the machine discharges completely cleaned fish in a very rapid and economical manner without injuring the fish and without waste.

5. Attention is called to the fact that the various elements of the device described hereinabove are driven in timed relation to each other so that the various operations are carried out without interference and in proper sequential arrangement.
10. For example, the intermittent movement of the feeding conveyor 2 is timed with the reciprocating movement of the pusher head 23 so that the prongs 7 of the conveyor are stationary at the time that the reciprocating head 23 pushes the
15. fish transversely onto table 8. Furthermore, the rocker means 40 actuated by the rocker shaft 39 are actuated at the beginning of the dwell period of the conveyor 2 and immediately before the pusher 23 is actuated so that the fish is liberated from contact with the prongs of the conveyor 2 by the rocker arm 40 and said rocker arm starts its return stroke before the pusher 23 moves the fish transversely.

Preferably the speed of the auxiliary conveyor mounted on sprockets 51 and 54 is correlated with the speed of the feeding conveyor and the speed of the cleansing conveyor 60-61. The spacing of the dogs 53 on the auxiliary conveyor should also be correlated with the speed of the feeding conveyor so that the fish are properly fed onto the auxiliary conveyor and the cleansing conveyor.

The speed of rotation of the various scraping means and saws is ordinarily adjusted to say between 200 and 1200 R. P. M., depending upon the type of saw, type of cleansing elements, and the like.

I claim:

1. In a fish cleaning machine, the combination of: a substantially horizontal feeding conveyor, cutting means adapted to behead fish carried by said feeding conveyor, separate tail cutting means, means for moving beheaded fish transversely on said conveyor into desired operative relation with said tail cutting means, and means for yieldably holding fish during beheading and tail cutting operations.

2. In a machine of the character described in claim 1, the combination of gage means for limiting the transverse movement of beheaded fish on said conveyor in accordance with thickness of said fish.

3. In a fish cleaning machine, the combination of a substantially horizontal feeding conveyor, means for intermittently driving said conveyor, cutting means adapted to behead fish carried by said feeding conveyor, separate tail cutting means, means for moving beheaded fish transversely on said conveyor in the desired operative relation with said tail cutting means during periods of dwell of said conveyor, and gage means for limiting said transverse movement in accordance with fish thickness.

4. In a machine of the character described, the combination of an intermittently driven feeding conveyor and a continuously driven cleansing conveyor, means for transferring fish from said feeding conveyor to said cleansing conveyor, and means for driving said feeding conveyor and cleansing conveyor from a common source, said means including a continuously driven shaft operably connected to said cleansing conveyor, a fixed stud shaft, a continuously driven gear member journaled thereon, said gear member being driven by said continuously driven shaft, a

pair of diametrically opposed pins carried by said driven gear member, a pinion on each of said pins, a fixed gear mounted on the stud shaft and in engagement with said pinions, a roller crank journaled on each of said pins, a yoke member provided with slots in alignment, said slots being adapted to receive rollers carried by said cranks, said yoke being connected to an intermittently driven shaft in axial alignment with said fixed stud shaft, said intermittently driven shaft being driven by said pinions and roller cranks, said intermittently driven shaft being operably connected to said intermittently driven feeding conveyor.

5. In an apparatus of the character described in claim 4, the combination of beheading means and de-tailing means in operative relation to said feeding conveyor.

6. In a machine of the character described in claim 4, the provision of beheading means in operative relation to said feeding conveyor, separate tail cutting means, means for moving fish transversely on said feeding conveyor into desired operative relation with said tail cutting means, and means for yieldably holding fish on said feeding conveyor during beheading and de-tailing operations.

7. In a machine of the character described, the provision of a feeding conveyor, beheading and de-tailing means in operative relation to said feeding conveyor, means for yieldably holding fish on said feeding conveyor during beheading and de-tailing operations, a cleansing conveyor, and means for transferring fish from said feeding conveyor to said cleansing conveyor, means for continuously driving said cleansing conveyor, and a continuously rotating driving means for said cleansing conveyor including means for translating continuous rotation into an intermittent movement of said feeding conveyor.

8. A machine of the character described in claim 7 in which the cleansing conveyor comprises a pair of opposing continuously driven endless members provided with opposing points adapted to enter, hold and move fish along a path of travel, and a floatingly suspended rippling saw, gutting tool, scraper, longitudinally acting wiping means and transversely acting wiping means in operative sequential relation to fish moving along said line of travel whereby fish may be gutted and cleaned while being advanced along said line of travel.

9. In a machine of the character described, the provision of a feeding conveyor provided with horizontally extending gill hooks along one edge thereof, beheading and de-tailing means in operative relation to said feeding conveyor, means for yieldably holding fish on said feeding conveyor during beheading and de-tailing operations, a cleansing conveyor, means for transferring fish from said feeding conveyor to said cleansing conveyor, means for continuously driving said cleansing conveyor, and a continuously rotating driving means for said cleansing conveyor including means for translating continuous rotation into an intermittent movement and intermittently driving said feeding conveyor.

10. A machine of the character described in claim 9 in which the beheading and de-tailing means are linearly spaced along said feeding conveyor, and means between said beheading and de-tailing means for moving beheaded fish transversely on said conveyor into the desired operative relation with said de-tailing means.

11. In a machine of the character described,

the combination of a feeding conveyor of the continuous type, longitudinally spaced gill hooks carried by one edge of said conveyor and extending in a substantially horizontal direction whereby fish may be positioned on said conveyor with heads protruding on one side thereof by forcing said gill hooks into gills on one side of said fish, beheading means on one side of said conveyor, separate tail cutting means longitudinally spaced from said beheading means, and means between said beheading means and tail cutting means for moving beheaded fish trans-

versely on said conveyor into desired operative relation with said tail cutting means.

12. A machine of the character described in claim 11 including a cleansing conveyor, means for transferring fish from said feeding conveyor to said cleansing conveyor, means for continuously driving said cleansing conveyor, and a continuously rotating driving means for said cleansing conveyor including means for translating continuous rotation into an intermittent movement of said feeding conveyor. 5 10
